UNITED STATES PATENT OFFICE.

DELBERT L. HARDEN, OF EUGENE, OREGON.

SANITARY DRINKING-FOUNTAIN AND FAUCET.

1,196,542.

Specification of Letters Patent. Patented Aug. 29, 1916.

Application filed March 28, 1914. Serial No. 828,003.

To all whom it may concern:

Be it known that I, DELBERT L. HARDEN, a citizen of the United States, residing at Eugene, in the county of Lane and State of 5 Oregon, have invented certain new and useful Improvements in Sanitary Drinking-Fountains and Faucets, of which the following is a specification.

My invention relates to an improved sanitary drinking fountain and faucet, and more particularly to such a device having pump mechanism associated therewith.

The primary object of the present invention is to provide a means whereby sanitary 15 drinking fountains may be practically combined and used in connection with ordinary pump mechanism and a domestic well such as are commonly found in rural districts, the invention being more especially adapted 20 for use where a number of persons are in the habit of drinking at the pump or well, for instance, in rural school house yards, etc.

As a further object of the invention, provision is made whereby the pump may be 25 utilized to force the water into a small pressure tank against a head of compressed air, and the pressure thus created is utilized to force the water vertically from the nozzle or bubbling valve of the drinking cup, the 30 discharge of water, being, however, controlled by a suitable valve whereby the supply is conserved.

The invention still further aims to provide a valve so constructed as to control, 35 when operated, not only the water supplied to the drinking cup, but, if desired, the water supplied to a suitable discharge spout or faucet associated therewith.

The above and additional objects are accomplished by such means as are illustrated 40 in their preferred embodiment in the accompanying drawings, described in the following specification and then more particularly pointed out in the claims which are 45 appended hereto and form a part of this application.

In describing my invention in detail reference will be had to the accompanying drawings wherein like characters denote like or 50 corresponding parts throughout the several views, and in which:—

Figure 1 is a vertical or longitudinal sectional view, partly broken away, of a pump operated combined sanitary drinking fountain and faucet constructed in accordance 55 with the present invention; Fig. 2 is a view

similar to Fig. 1, parts being shown in elevation, the section however being taken in a transverse direction; Fig. 3 is a side elevation of the device; Fig. 4 is a cross section 60 illustrating the arrangement of the operating mechanism interiorly of the fountain stand; and Fig. 5 is a top plan view of the device.

Referring now to the drawings by numerals, 1 designates, as an entirety, the fountain stand, the base of which is enlarged as at 2. A base plate 3 serves as a support for the said stand 1, said plate having a receptacle 4 integral therewith into which the overflow 70 or waste of the basin 5 is discharged. Said basin 5 is of ordinary construction having an outlet opening 6 formed therein as well as an inlet opening 7. Said opening 6 discharges the waste or overflow into a conduit 75 8 at one side of the stand, which conduit, is in communication with the chamber 4 by way of an opening 9 of the base plate 3.

A nozzle or bubbling valve 10 is positioned centrally within the bowl or basin 80 5, said valve being in communication and aligned with the inlet port or opening 7. A vertical pipe section 11, terminating at one end in a discharge spout 12 and at its opposite end in an enlargement 13, is arranged 85 concentrically within the basin or fountain stand 1, said section being annularly enlarged as at 13' to form a seat or casing for an operating valve 14. Ports 15, 16 and 17 are arranged in radial relation with respect to 90 the longitudinal axis of the said valve, the ports 15 and 17 being disposed at diametrically opposite points. Said valve is further provided with a handle 18 by means of 95 which a rotation of the said valve may be effected to provide for the water supply to either the discharge spout 12 or the bubbling valve 10. Said valve handle 18 is so arranged as to be operated to effect valve adjustment from a convenient point exteriorly 100 of the fountain stand. The enlargement 13 as well as the section 11 are preferably integral with the base plate 3, the former, that is, the enlargement 13, being in communication with a well pipe or tube 19 depending into the well from which the water supply necessary to the operation of the invention is derived. Said pipe or tube 19 has associated therewith the usual cylinder 20 with 105 in which is reciprocable a pump piston 21, the latter having connected thereto a piston rod 22 of a length sufficient to project

through the wall of the enlargement 13 and into the hollow fountain stand 1. A packing nut 23 may be provided to render the opening through which the piston rod 22 extends watertight. Pivotal connected as at 24 to the said rod 22 are a pair of links 25 so shaped or bent as to straddle the enlargement 13 in a manner apparent upon reference to Fig. 2 of the drawings. The links 25 are in turn pivotally connected as at 26 to a second pair of links 27, the latter being rigid with a shaft 28 to which a pump or operating lever 29 is secured. Said lever 29 being rigid with said shaft, it is apparent that oscillation of the lever will, through the connection afforded by the links 27 and 25 reciprocate the piston rod 22 and the piston 21 in a manner necessary to effect a proper pumping action.

20 Within the fountain stand 1 and in communication with the section 11 above noted, is a pressure tank 30 into which the water supply is forced by the pumping action whereby to utilize the pressure of the air compressed therein to force the water vertically from the nozzle or bubbling valve 10 when the valve 14 is set for such operation.

When it is desired that water be pumped and dispensed by way of the discharge spout 12, the valve 14 is rotated until ports 16 and 17 register respectively with the pipe section 11 and the discharge spout 12. When thus positioned, communication between said section 11 and the inlet opening 7 of the basin 5 is closed. Operation of the lever 29 will cause water to be pumped upwardly through the well pipe 19 into the enlargement 13, through the pipe section 11 and finally, out through the discharge spout 12. To provide for the dispensation of water by way of the nozzle 10, the valve 14 is rotated until ports 15 and 17 register respectively with the basin inlet opening or passage way 7 and the section 11, communication being shut off between said section 11 and discharge spout 12. The valve arrangement above noted is illustrated to advantage in Fig. 2. Operation of the lever 29 will cause water to be pumped from the source of water supply, against the pressure of the air within the pressure tank 30, which water, being under pressure, will, upon cessation of a pumping action, be forced vertically through the section 11 to the nozzle 10. A second opening 31 may be formed within the base plate 3 to provide for the escape of waste within the fountain stand 1 to the base 4 should such waste occur.

60 From the foregoing, taken in connection with the accompanying drawings it is apparent that by setting the valve until communication is closed between the pipe section 11 and the respective outlets 7 and 12, water may be pumped from the source of

the supply to compress the air within the tank 30, the water being in this manner conserved, and, when it is desired that it be dispensed, forced vertically through the nozzle by the pressure within the said tank, without manipulation of the lever 29; that waste or overflow within the basin 5 and interiorly of the fountain stand 1 is alternately discharged to the chamber 4 through the respective openings 9 and 31 of the base plate 3; and that by the novel arrangement of the links 27 and 25, force is directed to provide for the necessary reciprocation of the pumping above described.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:

1. In a combined drinking fountain and faucet, the combination with suitable pump mechanism, of a hollow upright stand; a basin formed upon the top of said stand; a supply pipe leading from said pump mechanism into said basin; a pressure reservoir connected into said supply pipe intermediate said pump mechanism and said basin; a fountain nozzle mounted upon the upper end of said supply pipe within said basin; a discharge pipe leading from said supply pipe to a point exterior to said stand; means operable to direct water to either said nozzle or said discharge pipe; an overflow reservoir formed at the base of said stand and having an opening communicating with the interior thereof; and a pipe leading from said basin to said reservoir.

2. In a combined drinking fountain and faucet, a hollow stand, a catch basin forming the stand top, a drinking fountain located within said basin, an operating handle secured to the stand base and oscillatable from a point in proximity to the said fountain, and a single valve operable from a point exteriorly of the stand to discharge water via either the fountain, faucet, or both.

3. In a combined drinking fountain and faucet, the combination with suitable pump mechanism, of a support for said mechanism, a basin mounted on the support, a water supply pipe leading into the basin, a fountain nozzle mounted on the supply pipe terminal, a discharge spout leading from the

supply pipe, means to direct water to either the nozzle or the spout, and means to carry off the overflow of the basin.

4. In a combined drinking fountain and faucet, the combination with manually operated pump mechanism, of a hollow upright stand, an overflow basin mounted on the stand top, a supply pipe leading into the basin, a fountain nozzle mounted on the supply pipe terminal, a discharge spout leading from the supply pipe to a point exteriorly of the stand, means operable to direct water to either the nozzle or the spout, a reservoir formed at the base of the stand, the said reservoir being open to the interior thereof, and a pipe leading from the basin to the reservoir, as and for the purpose set forth.
5. In a combined sanitary drinking fountain and faucet, a hollow upright stand having a basin formed on its top, an inlet pipe extending vertically throughout the stand and leading into the basin, a nozzle mounted on the pipe terminal and within the basin, a discharge spout leading from the pipe to a point exteriorly of the stand, means to direct the water to either the nozzle or the spout, a reservoir formed at the base of the stand, said stand having an opening formed in its base leading into said reservoir, a pipe leading from the basin to the reservoir, a single outlet pipe leading from the reservoir,

and pump operating mechanism disposed within the stand and operable from a point upon the exterior thereof, as and for the purpose set forth.

35

6. In a manually operated drinking fountain, the combination with suitable pump mechanism of a hollow upright stand; a basin upon the upper end of said stand; a supply pipe extending vertically throughout said stand and connecting said pump mechanism with said basin; a fountain nozzle mounted upon the upper end of said supply pipe within said basin; a pressure reservoir connected into said supply pipe intermediate said stand and connecting said pump mechanism and said nozzle; an overflow reservoir formed at the base of said stand and having an opening connecting with the interior thereof; a pipe within said stand one end thereof connecting with said basin and the opposite end thereof connecting with said overflow reservoir; and an operating handle attached to said pump mechanism adjacent the base of said stand and oscillatable from a point in proximity to said fountain.

In testimony whereof I affix my signature in presence of two witnesses.

DELBERT L. HARDEN.
